UNITED STATES PATENT OFFICE.

CHARLES D. YOUNG, OF ALTOONA, PENNSYLVANIA.

DRYING APPARATUS FOR RAILWAY-VEHICLES.

1,132,142.

Specification of Letters Patent. Patented Mar. 16, 1915.

Application filed April 30, 1913. Serial No. 764,622.

To all whom it may concern:

Be it known that I, CHARLES D. YOUNG, a citizen of the United States, residing at Altoona, in the county of Blair and State of Pennsylvania, have invented certain new and useful Improvements in Drying Apparatus for Railway-Vehicles; and I do hereby declare the following to be a full, clear, and exact description of the invention, such as will enable others skilled in the art to which it appertains to make and use the same.

This invention relates to an apparatus for drying painted railway vehicles, and has for its object to lessen the time and the cost now required to accomplish this end, as well as to improve the life and appearance of the finished covering.

With these and other objects in view, the invention consists in the novel details of construction and combinations of parts more fully hereinafter disclosed and particularly pointed out in the claims.

Referring to the accompanying drawings forming a part of this specification in which like numerals designate like parts in all the views:—Figure 1, is a diagrammatic cross sectional view in elevation, of an oven built in accordance with my invention; Fig. 2, is a perspective detail view of a short pipe section; Fig. 3, is a cross sectional plan view of the parts shown in Fig. 1; Fig. 4, is a longitudinal sectional view of the parts shown in Fig. 1; Fig. 5, is a side elevational view partly broken away of any oven; and Fig. 6, is a longitudinal sectional plan view of the parts shown in Fig. 5.

1 indicates the frame work preferably of steel and made to conform to the general shape of a car, 2 any suitable doors for closing the oven during the baking operation, 3 tracks on which a vehicle 4 can be accommodated, 5 an inside lining preferably of steel plate, 6 an outer plate, and 7 any suitable insulation between the plates 5 and 6. The doors 2 are insulated in a similar manner. Along the interior walls of the oven I preferably place a plurality of rows of steam pipe 9, fed from the branch supply pipes 10, joined to the main feed pipe 11 as shown. The pipe 10 may be further provided with extensions 14 joining a plurality of manifolds 12, near the floor, and having tapped into them at intervals the short lengths of pipe 13, as best seen in Figs. 2, 4 and 6. By this means I am able to provide a very

large radiating surface, and with say a steam pressure of one hundred pounds (100 lbs.) I can maintain an oven temperature of 250° F. Further my structure is such, 60 as will be clear from the drawings, that no metallic connections between the inner and outer surfaces of the oven are had, and therefore the loss of heat from the radiators is reduced to a minimum. 65

In order to provide for an efficient ventilation the structure has a plurality of preferably rectangular inlets or openings 16 near the floor, and a plurality of spaced ventilators 17 of any suitable type in the 70 roof. By this means the fresh air which is necessary for the proper drying of the paint is had, while at the same time an exit is provided for the volatile matter given off.

18 represents suitable drain pipe, and 19 75 suitable tie members for holding together the frames 1 and stiffening the structure.

It is essential in drying car bodies that the heat be evenly distributed throughout. For if the ends of the car for example, dry 80 harder than the center, owing to a higher temperature at the ends, the paint would blister, unless a different proportion of vehicle be placed in the paint to be applied to the ends, which is, of course, impracticable. 85 My construction it will be seen, avoids these objections by providing a uniform temperature throughout the length of the car. That is to say, I provide for the admission of air along the bottom of the oven and above the 90 level of the rails, employing the openings or members 16 to assist the ventilation and equal distribution of the air. I also provide ventilators at the top to insure the proper equal distribution of heat throughout. 95 Further, the arrangement just described provides a circulation of air along the sides of the oven which causes the gases and depleted air to pass out.

In order that the operation of my invention may be clearly understood in the case of a car it is said:—A priming coat may be first given the car in the paint shop, whereupon it is moved into the oven and baked for say three hours, the temperature 105 at first being say 160° F. whereupon it may be raised say 1° F. per minute until 250° F. is reached. The oven is now held at this latter temperature for the rest of the three hours, whereupon the car is withdrawn, allowed to cool sufficiently to work upon, and its surfaces glazed and puttied where found 110

necessary to fill up depressions and uneven places. The car may now receive its first surfacing coat and be returned to the oven for three hours, baked as before, be removed, cooled and coated again. This may be repeated as often as desired, when the outside surface is finally rubbed down with emery cloth and oil and the colors are applied.

Each color coat may be baked as above, 10 when the lettering, striping etc. is applied, and the varnish coatings are applied. These latter coatings can be likewise baked, but it is preferred to begin the operation at say 120° F. and to not let the temperature rise 15 above say 150° F. The interior of the car is next rubbed to give it a "flat finish" and the painting of the car is completed.

All the above operations can be conveniently carried out with my oven in say from 20 six to eight days, while under the present system it would require from sixteen to eighteen days to accomplish the same results.

In addition to the above various paints and varnishes have now been prepared so 25 they are especially adapted for this baking process, and are found to have a greater elasticity, a greater durability, a better appearance and a longer life than those heretofore applied in the old way. It follows from 30 this that the baking process combined with these said paints and varnishes materially lessens the checking and cracking heretofore encountered, and as the work can be done under standard uniform conditions, uniform 35 results are also attained. Further, by uniformly heating the car in the first place and thoroughly drying the same before the first priming coat is applied, all objectionable moisture is removed, and a far better hold 40 is attained by said coat than has been heretofore possible. In other words, before the advent of steel cars, it was not practical to thus heat the wooden cars, and since the advent of said steel cars, no one, so far as I know, 45 has discovered the advantages of making the great surface area of a steel car of a uniform nature so far as moisture is concerned, before applying the priming coat, nor even of making such area uniform for the succeeding 50 ing coats. This uniformity of surface affording a better grip for my coats, constitutes an important feature of my invention, for it aids in preventing the painted surface from going to pieces in spots as heretofore. 55 In addition to the above, not only does the coated surface have a longer life, a better appearance, and can be finished in a less time, but the material itself costs less without any extra labor charge.

It is obvious that those skilled in the art 6 may vary the details of construction, as well as the arrangement of parts without departing from the spirit of the invention, and therefore I do not wish to be limited to the above disclosure, except as may be required 6 by the claims.

What I claim is:—

1. In an apparatus for drying or baking 70 a railway vehicle, the combination of a chamber comprising a heat insulated covering; a door for said chamber; a track on which said vehicle may enter said chamber; openings for the admission of fresh air near the bottom of said chamber; ventilators for the exit of gases at the top of said chamber; 75 and steam heating means at the sides and bottom of said chamber for producing any desired uniform temperature in said chamber, substantially as described.

2. In an apparatus for drying or baking 80 a railway vehicle, the combination of a chamber comprising a heat insulated covering consisting of a frame work and an inner and an outer shell having insulation between them; a door for said chamber comprising 85 two plate members with insulation between them; a track on which said vehicle may enter said chamber; openings for the admission of fresh air near the bottom of said chamber; ventilators for the exit of 90 gases at the top of said chamber; and steam heating means at the sides and bottom of said chamber comprising a plurality of pipe, manifolds and short lengths of pipe projecting from said manifolds for producing 95 any desired uniform temperature in said chamber, substantially as described.

3. In an apparatus for uniformly drying and baking railway vehicles throughout 100 their length, the combination of a frame-work; a heat insulated shell supported by said frame work; heat insulated doors closing said shell; a track for vehicles entering said shell; means for the admission of air along the bottom of said shell above said 105 rails; ventilators at the top of said oven; and heat radiating means along the sides of said oven; whereby a circulation of air along the said sides is secured, to insure an equal distribution of temperature throughout and 110 to carry away gases and depleted air, substantially as described.

In testimony whereof I affix my signature, in presence of two witnesses.

CHARLES D. YOUNG.
